UNITED STATES PATENT OFFICE.

WILLIAM E. JAQUES, OF GRAND RAPIDS, MICHIGAN.

EVAPORATING APPARATUS.

No. 798,681.

Specification of Letters Patent.

Patented Sept. 5, 1905.

Application filed December 11, 1902. Serial No. 134,803.

To all whom it may concern:

Be it known that I, WILLIAM E. JAQUES, a citizen of the United States of America, residing at Grand Rapids, in the county of Kent 5 and State of Michigan, have invented certain new and useful Improvements in Desiccating or Evaporating Apparatus; and I hereby declare the following to be a full, clear, and exact description of the invention, such as will enable others skilled in the art to which it pertains to make and use the same.

This invention relates to improvements in apparatus for desiccating or evaporating liquids or semiliquids—such, for instance, as 15 milk, cream, eggs, and the like—capable of being agitated, whipped, or beaten into a foam or froth.

The primary object of this invention is to rapidly evaporate or desiccate a liquid or semiliquid of the character indicated in a simple, 20 efficient, and economical manner, without resulting in a deterioration of or injury to the resulting product.

Another object is to agitate, whip, or beat 25 the liquid or semiliquid into a foam or froth, then convey the foam or froth in a horizontal or approximately horizontal plane through and next below a current of heated air, and then permit the dry or partially-dried solid 30 particles to descend or settle through an ascending current of heated air.

With this object in view and to realize other advantages hereinafter appearing the said invention consists in certain features of construction and combinations of parts hereinafter described, and pointed out in the claims.

In the accompanying drawings, Figure 1 is a side elevation, largely in section and diagrammatic, of apparatus embodying the said 40 invention. Fig. 2 is a vertical section on line 2 2, Fig. 1, looking in the direction indicated by the arrow. Fig. 3 is a vertical section on line 3 3, Fig. 1, looking in the direction indicated by the arrow.

45 Referring to the drawings, A designates a receptacle which is supplied with the liquid or semiliquid which is to be agitated, whipped, or beaten into a foam or froth within the interior chamber of the said receptacle, and p represents a valved chute or pipe arranged to 50 feed the milk or liquid into the lower portion of the chamber of the said receptacle. The pipe p is provided with a normally closed valve q. Within the lower portion of the 55 chamber of the receptacle A is an agitator or beater, which comprises, preferably, a verti-

cally-arranged hollow shaft 40 and a vertically-arranged solid shaft 42, extending through the hollow shaft 40. The shafts 40 and 42 are arranged centrally of the lower portion of the receptacle A and are driven in opposite directions, respectively. The hollow shaft 40 is provided within the chamber of the receptacle A, in close proximity to the bottom of the said chamber, with radial arms 60 43, which have upwardly-projecting vertically-arranged blades 44. The solid shaft 42 extends into the chamber of the receptacle A above the blades 44 of the arms of the hollow shaft and is provided at its upper end with radial arms 45, which have depending vertically-arranged blades 46, which are arranged as required to avoid interference with the location and operation of the blades 44 of the hollow shaft and coöperate with the last-mentioned blades in agitating, whipping, or beating the liquid or semiliquid which is to be whipped or beaten into a foam or froth within the said receptacle A.

The shaft 42 is operatively provided with a spur-gear 47, which is in mesh with a spur-gear 48, with which a suitably-applied driving-shaft 50 is operatively provided, whereas the other shaft 40 is operatively provided with a spur-gear 52, which is driven, through the medium of a suitably-applied intermediate spur-gear 54, from a spur-gear 53, operatively mounted on the driving-shaft 50. The froth or foam formed and accumulating within the upper portion of the chamber of the receptacle A over the agitator or beater within the said chamber is shoved or fed from the said chamber onto an endless conveyer, which comprises an endless imperforate belt B and is arranged in a horizontal or approximately horizontal plane. The belt B leads over and frictionally engages pulleys D, which are applied and supported in any approved manner. The belt B forms the traveling bottom of a drying-chamber E and extends, therefore, longitudinally of the said chamber.

The receptacle A is arranged in suitable proximity to the receiving end of the drying-chamber E, and an open-ended trough G extends over the top of the receptacle A and bridges the space between the said receptacle and the belt B and has its bottom closely overlapping the said belt. The chamber of the trough G communicates at the top of the receptacle A, as at g, with the chamber of the said receptacle. The foam or froth formed within the receptacle rises into the trough G

and is shoved or fed longitudinally of and from the said trough onto the belt B by an endless conveyer, which comprises an endless belt H, leading over and frictionally engaging pulleys J, which are supported in any approved manner. The belt H is provided at its outer side with wings K, which are arranged transversely of and at suitable intervals longitudinally of the belt and project outwardly from the said side of the said belt. The arrangement of the parts is such that the belt H somewhat overlaps the belt B, and the wings K in passing through the trough G during the actuation of the belt H extend into close proximity to the bottom of the said trough. The belt H is actuated in the direction (indicated by the arrow) required to feed the froth or foam from the chamber of the receptacle A to the belt B. The wings K are preferably spaced such a distance apart that the passage-way formed by the trough G is always occupied by wings K, as shown in Fig. 1, so that a current of air to the said drying-chamber E from and through the receptacle A cannot obtain, and the belt H, it will be observed, forms a top or cover for the interior chamber of the said trough.

One of the pulleys J is operatively mounted on a suitably-supported driving-shaft Q, which is provided with a driving-wheel R. One of the pulleys D is operatively mounted on a suitably-supported shaft T, which is operatively provided with a sprocket-wheel U, operatively connected by a chain W with a sprocket-wheel Z, operatively mounted on a shaft L, which is intergeared, as at N, with the shaft Q. Obviously, therefore, the belt B is actuated in the same direction required to feed the foam or froth delivered thereon by the belt H longitudinally of the drying-chamber E toward the discharging end of the said chamber.

Next over the drying-chamber E is arranged a hot-air chamber l, which contains a steam radiator or heater m, applied and operated in any approved manner. The chamber l extends preferably from over the receiving end of the drying-chamber E toward the discharging end of the said chamber a suitable distance. The chamber l is provided at the top with an air-inlet n and extends somewhat over the belt H. The chamber l is provided adjacent to the belt H with an arc-shaped wall o, which extends concentrically of the shaft Q, and is arranged far enough from the belt H to accommodate the location and operation of the said belt and the wings K of the belt.

The side walls of the trough G form an extension of the side walls of the drying-chamber, and the last-mentioned walls are extended upwardly along the outer side of the wall o at the sides of the path of the wings K of the belt H, as at u. The wall o and the upward wall extensions u form an open-ended hood

embracing the path of the wings K such a distance relative to the spacing apart of the wings K that one wing K is at all times in position obstructing the space between the wall o and the belt H—that is, that as soon as a wing K during the operation of the belt H is in position to leave the said space the next succeeding wing K will be in position to enter the said space. It will be observed, therefore, that the construction and arrangement of the parts are such that external air cannot freely enter the forward end of the drying-chamber E at any time.

The upper portion of the chamber E, about centrally between the ends of the said chamber, is provided with a partition j, which extends transversely of the said chamber. The bottom of the hot-air chamber l, which bottom is instrumental in forming the top of the drying-chamber E, is formed, being provided forward of the partition j—that is, between the said partition and the belt H—with perforations s, which establish communication between the chamber l and the drying-chamber E.

The drying-chamber E communicates at its rear end and at the top with a vapor-conducting passage-way or outlet c, which connects and communicates with the inlet of a suitably-operated pump or suction-creating device v.

Another drying-chamber a is vertically arranged next below the rear end of the belt B and extends upwardly around the rear end of the said belt and there communicates with the rear and discharging end of the drying-chamber E. The passage-way c is therefore also the vapor-outlet of the vertically-arranged drying-chamber a. Hence both drying-chambers E and a have a vapor-outlet c in common. The chamber a is formed by a casing b. The chamber a communicates at the top with the drying-chamber E and centrally of its lower end has a downwardly-discharging outlet d. The lower end portion e of the casing b tapers downwardly, and the outlet d is formed at the lower end of the said lower end portion e of the said casing.

A heating-jacket or air-heating chamber f surrounds the lower end portion e of the casing b and extends, preferably, a suitable distance below the lower end of the chamber a, and a steam radiator or heater h is arranged within the said jacket or chamber f.

A suitably-supported imperforate deflector 10 overhangs the upper end of the drying-chamber a and is arranged below the vapor-outlet c. The deflector 10 forms one of the side walls of a trough 12, whose interior chamber is arranged to receive any water resulting from condensation of vapors within the vapor-outlet c, and a drain-pipe 11 communicates with the lowest portion of the chamber 12.

A conveyer-containing case 30, which is arranged in a horizontal plane next below the

outlet *d* of the chamber *a*, extends outside of the said jacket or hot-air chamber *f*. An aperture 32, which is formed in the top of the case 30, registers with the outlet *d* and consequently forms the inlet of the said case. A screw conveyer 33 is arranged within and longitudinally of the case 30 and extends from end to end of the said case. The conveyer 33 extends from within the receiving end of the case 30—that is, from in under the inlet 32 of the said case—to the opposite or discharging end of the said case. The case 30 is provided at the last-mentioned end and externally of the chamber or jacket *f* and at the bottom with a downwardly-discharging opening or outlet 34, and the conveyer is operatively provided at one end and outside of the said case with a driving-wheel 35, to which power is applied in any approved manner.

The jacket or chamber *f* is provided at its lower end with lateral apertures or air-inlets 60, arranged at suitable intervals around the said chamber, and the downwardly-tapering lower end portion *c* of the casing *b* is foraminated, having lateral apertures or perforations 62 arranged a suitable distance above its lower extremity and establishing communication between the drying-chamber *a* and the hot-air chamber *f*. The apertures 62 constitute the air-outlets of the chamber *f* and the air-inlets of the drying-chamber *a*, and heated air passes, therefore, through the said perforations 62 into the said drying-chamber. The lower end portion *c* of the casing *b* is provided internally with funnel-shaped guards 63, arranged to prevent solid particles which descend or settle within the drying-chamber *a* from passing into the hot-air chamber *f* through the perforations 62.

The operation of the hereinbefore-described apparatus is as follows: The pump or suction-creating device *v* is operated to create enough suction in the vapor-outlet *c* to cause a current of heated air to pass from the hot-air chamber *f*, through the perforations *s*, into and through the drying-chamber *E*, and in under the partition *j* in its passage rearwardly longitudinally of the said drying-chamber. A current of heated air therefore obtains along and next to or in close proximity to the belt *B*. Heated air is also caused to pass into the drying-chamber *a* at the perforations 62 and a current of hot air upwardly through the chamber *a* obtains. The liquid or semiliquid to be desiccated or evaporated and supplied to the receptacle *A* is agitated, whipped, or stirred by the operation of the shafts 40 and 42 into a froth or foam, which rises into the path of the wings *K* of the belt *H*, and the said belt is actuated to cause the said foam or froth to be shoved or fed by the wings *K* along the trough *G* onto the belt *B*, which is actuated to feed the froth or foam thus delivered thereto rearwardly, and thereby expose the said material to the current of heated

air passing rearwardly over the belt *B*. The said material is dried or partially dried on the belt *B*, and the dried or partially-dried material is discharged from the belt *B* into the upper end of the drying-chamber *a*, where any remaining trace of moisture is removed from the partially-dried material by the current of heated air passing upwardly through the said chamber *a*. Any moisture absorbed by the upward current of air within the drying-chamber *a* escapes with the said air at the vapor-outlet *c*. Any solid constituents of the froth or foam to be evaporated or desiccated which pass to and impinge against the downwardly-facing surfaces of the deflector 10 are deflected or returned downwardly, and hence the escape of solid particles to the vapor-outlet *c* is prevented. A suitably-applied scraper *r* is arranged within the upper portion of the drying-chamber *a* in position to remove from the belt *B* any material adhering to the said belt. The dried or partially-dried solid particles descending from the belt *B* into the drying-chamber *a* during the operation of the apparatus settle by gravity into the lower portion of the said chamber, and obviously the said particles descend more slowly as they become drier. The solid particles thus descending through the lower portion of the drying-chamber *a* will be perfectly dry by the time they reach the discharge aperture or outlet *d* of the said chamber and will pass through the inlet 32 of the conveyer-case 30 and be fed by the conveyer 33 to the outlet 34 of the said case.

The evaporating or desiccating process carried out by the operation of the apparatus hereinbefore described constitutes the subject-matter of a contemporaneous application filed simultaneously with the filing of this application.

What I claim is—

1. Desiccating or evaporating apparatus comprising the following: a receptacle; means for agitating a liquid or semiliquid within the said receptacle into a froth; a drying-chamber arranged externally of and in suitable proximity to the aforesaid receptacle; a conveyer arranged to carry the material to be evaporated or desiccated through the drying-chamber; means for operating the conveyer, means for establishing a current of heated air through the drying-chamber; and means for removing the said froth from the said receptacle onto the said conveyer.

2. The combination, with means for agitating a liquid or semiliquid into a froth, of a drying-chamber; a conveyer arranged to receive the froth and carry the material longitudinally of and through the drying-chamber; means for operating the conveyer; means for establishing a hot-air current through the drying-chamber, and means for delivering the froth to the conveyer.

3. The combination, with a receptacle, and

an agitator for agitating a liquid or semi-
liquid within the said chamber into a froth,
of a drying-chamber arranged externally of
and in suitable proximity to the aforesaid re-
ceptacle; an endless belt forming the bottom
5 of the drying-chamber; means for actuating
the belt; means for establishing a current of
heated air through the drying-chamber, and
means for conveying froth from over the said
10 agitator toward and onto the belt.

4. The combination, with a receptacle, an
agitator arranged within the lower portion of
the said receptacle, and means for operating
the said agitator, of a drying-chamber ar-
15 ranged in a horizontal or approximately hori-
zontal plane and extending from adjacent the
said receptacle; an endless belt forming the
bottom of and extending longitudinally of the
said chamber; means for operating the said
20 belt; an open-ended trough arranged to dis-
charge onto the said belt and in open relation,
at the bottom, with the interior chamber of
the aforesaid receptacle above the aforesaid
agitator; means for conducting vapor from
25 the drying-chamber, and means for conveying
froth rising into the trough from the said re-
ceptacle along the trough and onto the afore-
said belt.

5. The combination, with a receptacle;
30 means for agitating a liquid or semiliquid
within the said receptacle into a froth; a dry-
ing-chamber arranged externally of and in
suitable proximity to the aforesaid receptacle;
a conveyer arranged to carry the material
35 to be evaporated or desiccated through the
drying-chamber, and means for conducting
vapors from the said chamber, of an endless
belt provided, at its outer side, with project-
ing wings which extend transversely of the
40 belt and are arranged to feed froth from the
aforesaid receptacle toward and onto the afore-
said conveyer, and means for operating the
said belt.

6. The combination, with a receptacle, and
45 means for agitating a liquid or semiliquid
within the said receptacle into a froth, of a
drying-chamber arranged externally of and in
suitable proximity to the aforesaid receptacle;
an endless belt instrumental in form-
50 ing the bottom and extending longitudinally
of the said chamber; an open-ended trough
extending from and communicating with the
upper portion of the chamber of the afore-
said receptacle to and discharging onto the
55 said belt; means for conducting vapors from
the drying-chamber; another endless belt
forming a top or cover for the trough and
provided, at its outer side, with projecting
wings arranged to feed froth along the trough
60 to the drying-chamber, and means for oper-
ating the endless belts.

7. The combination, with a drying-cham-
ber; an endless belt for carrying material
through the said chamber, and means for con-
65 ducting vapors from the drying-chamber, of

another endless belt provided, at its outer
side, with projecting wings arranged to feed
froth into the drying-chamber, and an open-
ended hood overhanging the winged belt above
the other belt.

8. The combination, with a drying-cham-
ber; an endless belt for carrying material
through the drying-chamber; means for op-
erating the belt; a partition arranged trans-
versely of the upper portion of the drying-
70 chamber at a suitable point between the ends
of the chamber; an air-chamber arranged
above the drying-chamber and communicat-
ing with the drying-chamber forward of the
said partition; means for heating the air sup-
plied to the said air-chamber, and means for
80 permitting the escape of vapors from the dry-
ing-chamber at the rear end of the said cham-
ber.

9. The combination, with a receptacle; 85
means for agitating a liquid or semiliquid
within the said receptacle into a froth; an up-
right drying-chamber arranged a suitable dis-
tance from and laterally of the aforesaid re-
ceptacle, and means for establishing a current 90
of air upwardly through the said drying-
chamber, of an upper drying-chamber com-
municating, at one end, with the upper end
of the aforesaid upright drying-chamber and
extending into suitable proximity to the afore-
95 said receptacle; means for conveying the froth
from the said receptacle to the upper drying-
chamber, and means for conducting the ma-
terial to be desiccated or evaporated through
the said upper chamber into the upper end of
the said upright chamber.

10. The combination of means for frothing
a liquid or semiliquid, means for establishing
a current of heated air in one plane, means
for establishing a current of heated air in an-
other plane at an angle to the first-mentioned
105 plane, and means for conveying froth along
the first-mentioned air-current into the other
air-current.

11. The combination of means for frothing
a liquid or semiliquid, means for establishing
an ascending current of heated air, means for
conveying the froth to the ascending air-cur-
rent, and means for partially drying the froth
110 during its passage to the said air-current.

12. The combination of means for frothing
a liquid or semiliquid, an upright drying-
chamber, an initial chamber arranged at one
side of and discharging into the upper end of
the upright drying-chamber, and means for
120 feeding froth through the initial drying-cham-
ber into the upright drying-chamber.

In testimony whereof I sign the foregoing
specification, in the presence of two witnesses,
this 6th day of December, 1902, at Cleveland,
125 Ohio.

WILLIAM E. JAQUES.
